UNITED STATES PATENT OFFICE.

GUSTAV LUDWIG HERTZ, OF EINDHOVEN, NETHERLANDS, ASSIGNOR TO N. V. PHILIPS' GLOEILAMPENFABRIEKEN, OF EINDHOVEN, THE NETHERLANDS.

ELECTRIC DISCHARGE TUBE.

No Drawing. Application filed February 18, 1925, Serial No. 10,105, and in the Netherlands April 1, 1924.

This invention relates to electric discharge tubes and more particularly to electric discharge tubes having a positive column light for lighting purposes.

5 It is known to introduce into such discharge tubes a gaseous filling of neon, whereby the light radiated by the said tubes acquires red colour.

It is also known to introduce into discharge tubes having a positive column light a little mercury in the form of a mercury drop, in addition to a gaseous filling of neon. By reason of the heating to which the tube during the discharge is exposed, the mercury volatilizes and at a certain temperature the vapour pressure of the mercury increases such that the mercury vapour begins to participate in the discharge and the positive light emitted by the discharge tube is even produced essentially by radiation of mercury atoms with the result that the red colour changes to a blue one. Discharge tubes of this kind have the disadvantage that if for any reason the temperature of the tube becomes too low (for example by reason of a low temperature of the surrounding open air), the vapour pressure of the mercury may acquire such a low value that the mercury practically no longer takes part in the discharge and the blue mercury light changes to the red neon light.

Now it has been found that the said disadvantage is reduced or eliminated, if instead of neon some other rare gases are used, for example argon, but krypton and xenon also give favourable results.

According to the invention a gaseous filling is introduced into a discharge tube with positive column light, which gaseous filling comprises argon and mercury vapor. The gaseous filling may consist of argon, krypton, xenon and mercury vapor. Preferably

a gaseous filling of argon and mercury, the argon pressure of which is above 4 millimetres of mercury will be used. Discharge 45 tubes according to the invention are capable of still producing mercury light at temperatures at which a discharge tube having positive light and filled with neon and mercury already produces neon light. This is a very 50 remarkable phenomenon, as the exciting potential of argon is lower than that of neon. One would therefore expect that at a temperature at which a neon mercury discharge tube produces neon light, an argon mercury 55 discharge tube of all others would produce only argon light, whereas experiment discloses that at certain temperatures the contrary is the case.

A great advantage of the discharge tubes 60 according to the invention consists in that their operating voltage is lower than that of discharge tubes having a positive column light and a neon mercury filling. The efficiency of discharge tubes according to the 65 invention will likewise be greater than that of discharge tubes having a positive light and a gaseous filling of neon and mercury.

What I claim is:

1. A discharge tube for positive column 70 light, the gaseous filling of which comprises argon and mercury vapor.

2. A discharge tube for positive column light, the gaseous filling of which consists of argon, krypton, xenon and mercury vapor. 75

3. A discharge tube for positive column light, the gaseous filling of which consists of argon having a pressure above 4 millimetres of mercury pressure and of mercury vapor. 80

In testimony whereof I affix my signature, at the city of Eindhoven, this 20th day of January, 1925.

GUSTAV LUDWIG HERTZ.
